UNITED STATES PATENT OFFICE

RALPH BAERMAN, OF RUSHFORD, MINNESOTA

FOLDING DISPLAY CABINET

Application filed October 17, 1929. Serial No. 400,247.

My invention relates to folding display cabinets particularly, though not exclusively, for the display of specimen flowers, etc., in the sale of bulbs, roots and seeds, an object of the invention being to provide a cabinet of simple, durable and inexpensive construction and one which is readily portable in form having minimum over-all dimensions, and which is adapted readily to be expanded for the purpose of presenting an effective and relatively extensive display.

Another object of the invention resides in providing a display cabinet having two foldable sections adapted to be extended to display the contents of the cabinet and to be collapsed to encase the contents and to permit of convenient handling in safety to both cabinet and contents.

Another object of the invention resides in forming each of said sections with an open front and an open end and in hingedly connecting said sections together, whereby they may be relatively disposed open end to open end in the extended arrangement of the cabinet and open front to open front in the collapsed arrangement thereof.

A further object of the invention resides in providing the cabinet sections with racks, a rack in one constituting a continuation of a rack in the other, in the extended arrangement of the cabinet.

A feature of the invention resides in providing a hinged member adapted to form a closure for the open ends of the cabinet sections in their folded relation, said member being adapted to be swung out of its end closing position to permit of the unfolding of the cabinet sections.

An object of the invention resides in providing said sections with caster wheels for supporting the cabinet, and in utilizing said closure member for bracing the cabinet when the sections thereof are in extended relation.

Another object of the invention resides in providing hinged top members for the cabinet sections, adapted to be swung back therefrom and, in such position, to be supported by said closure member.

With the foregoing and other objects in view, which will appear in the following de-

scription, the invention resides in the novel combination and arrangement of parts and in the details of construction hereinafter described and claimed.

In the drawings:

Fig. 1 is a perspective view of a cabinet illustrating an embodiment of my invention and showing the parts in folded relation.

Fig. 2 is a perspective view of the cabinet, illustrating the parts in extended relation.

Fig. 3 is a plan view of the structure shown in Fig. 1.

Fig. 4 is a plan view of the structure shown in Fig. 2, the cover members being in closed position.

Fig. 5 is an elevational sectional view taken as on line 5—5 of Fig. 3.

In the sale of certain commodities, such as bulbs, roots, seeds and the like, considerable advantage is gained by displaying specimens of the flowers, spikes and such growths as may be expected to mature therefrom.

Heretofore the displays of such specimens have been almost entirely confined to the nursery and gardening sites and to flower shows or exhibitions to which the large percentage of potential purchasers are not attracted. The problem of reaching such purchasers may be met by the employment of what may be termed a portable flower show adapted to be transported from house to house in the canvassing of individuals not likely otherwise to have guidance through the medium of actual specimens in the selection of bulbs, seeds, etc. To provide for such individual shows or displays, it becomes highly desirable that an appropriate display cabinet be had for the purpose. The present invention provides a cabinet particularly adapted for such purpose.

The illustrated embodiment of my invention comprises a cabinet consisting of two sections which I have indicated in their entirety at A and B. The section A consists of a rear or side wall 10 and an end wall 12 of a height substantially equal to the full height of the cabinet and of a front wall 13 of considerably less height connected to the end wall 12 and to a filler 14 disposed between the said front wall 13 and the rear wall 10.

Attached to the said wall structure are two shelves 15 and 16, both of which are secured at their ends to the end wall 12 and the filler 14. Shelf 15 is attached to rear wall 10 and shelf 16 to the front wall 13, while a riser 17 is disposed between the two shelves. These two shelves serve as racks for the reception of a number of vases 18 which rest upon supports 19 and 20 disposed immediately beneath the said shelves 15 and 16 and secured to the riser 17 and front wall 13 respectively. The shelves 15 and 16 are apertured, as designated at 21, to receive the vases 18, while the supports 19 and 20 are recessed, as designated at 22, to receive the ends of said vases in a manner to support and hold the same in upright position within the cabinet. By means of this construction, a section is provided which is open at the top and open at the front 20 above the front wall 13 and also open at one end above the filler 14 and the shelf structure of said section.

Section B is constructed similar to section A and comprises a rear wall 110, an end wall 112 and a front wall 113, together with shelves 115 and 116, all connected together in identically the same manner as the corresponding parts of section A, except that they are arranged in inverse order to cause the 30 sections to have a left hand and right hand relation with one another, as best shown in Fig. 2.

The said section B similarly comprises a filler member 114, a riser 117 and supports 35 119 and 120, all arranged in exactly the same manner as the corresponding parts in section A. The shelves 115 are similarly apertured at 121 and the supports 119 and 120 recessed at 122 to support the vases 18 in the same manner as previously described.

The two sections A and B are hinged together along the front walls 13 and 113 thereof by means of hinges 23 which are disposed at the open ends of the cabinet. 45 By means of these hinges, the two sections A and B may be swung from the extended position shown in Fig. 2, where the shelves 15 and 115 and 16 and 116 lie in continuation of one another to the collapsed position shown in Fig. 1. All of the parts of these sections lie flush at the open ends thereof, so that said sections fit snugly together when extended, making a continuous display cabinet open along the front thereof. When the 55 two sections A and B are swung about the hinges 23 into their folded position, the front walls 13 and 113 are brought face to face, which has the effect of closing the fronts of the cabinet sections, as clearly shown in Figs. 60 1 and 3. This disposition of the two sections leaves the open ends of the cabinet sections exposed as well as the tops thereof. For closing the ends of the two cabinet sections when in folded relation, a single closure 24 65 is employed which is of a width equal to the

combined width of the collapsed sections and of a height equal to the total height of the cabinet. This closure is hinged through hinges 25 to the rear wall of one of the sections which, in the embodiment illustrated, is the wall 10 of section A. When the cabinet is collapsed, the closure 24 lies flush against the open ends of the two sections A and B and along the fillers 14 and 114 thereof, completely closing the ends of said sections. When the said closure is swung outwardly, as shown in Figs. 2 and 4, it is clear of the cabinet proper and permits of the unfolding of sections A and B and the bringing thereof into end to end relation, as shown in said Figs. 2 and 4.

The sections A and B are constructed with legs 26 and 126 to which caster wheels 26^a and 126^a are applied. The closure 24 is constructed with a leg 27 which, when the cabinet is in extended position, as shown in Figs. 2 and 4, serves to brace the cabinet against tipping backward.

For closing the upper portion of the cabinet, two covers 28 and 128 are employed which are hingedly connected to the rear walls 10 and 110 of sections A and B through offset hinges 29 and 129. These covers may be swung shut to close the top of the cabinet, as shown in Figs. 1, 3 and 5, or they may be swung open into the position shown in Fig. 2 to fully expose the flowers or other specimens displayed within the cabinet. The offset hinges 29 and 129 cause the said covers to lie flat upon the upper edges of the rear walls 10 and 110 and the end walls 12 and 112 of the cabinet proper and at the same time permit of the swinging of the said covers back, in a manner to permit of the same resting upon the upper edge of the closure 24. Said closure, in this manner, serves to form a stop or a support for supporting the covers when in fully open position. To support both of these covers jointly, the closure 24 may be set at a slight angle, as shown in Fig. 4, or it may be formed with a stop or cleat (not shown) serving to support the cover 128 when said closure is in fully extended position.

Dowel pins 112^a (Fig. 2) projecting from the exposed edge of end wall 112 of cabinet section B correspond with holes 12^a in the exposed edge of end wall 12 of cabinet section A. These dowel pins fit into said openings when said sections are folded together and thus free the hinges 23 from racking strains, which otherwise would be imposed upon them in the handling of the closed cabinet or in the wheeling thereof along rough and uneven side walks and other supporting surfaces. Hooks 12^b fastened to the end wall 12 and adapted to coact with eyes 112^b fastened to the end wall 112 serve to secure the cabinet sections A and B in folded relation. A hook 110^a pivoted on back wall 130

110 of cabinet section B is adapted to engage a pin 24^a projecting from the free edge of the closure 24 in the folded position of said closure (Fig. 1) and releasably hold the closure in such position.

5 In the use of the device, the various flowers, spikes or other specimens to be displayed are inserted into the vases 18, which are preferably partially filled with water. 10 When the cabinet has been transported to the desired place and it is the wish of the attendant to display the flowers, the hooks 12^b are freed from the eyes 112^a and the hook 110^a from the pin 24^a. The closure 24 is then 15 swung into the position shown in Fig. 4, and the cabinet section B swung about the hinges 23 to bring the display racks 15, 115 and 16, 116 into continuation of one another. The covers 28 and 128 may then be opened and 20 rested upon the upper edge of closure 24, giving the observer a full view of the articles displayed within the cabinet. When it is desired to collapse the cabinet, the reverse order of procedure is adopted and the parts 25 rearranged as shown in Fig. 1 to fully close the cabinet and conceal the contents thereof. When in collapsed position, the flowers are fully sheltered and protected and the cabinet may be readily handled and transported in 30 the desired manner.

My invention is highly meritorious in that an extremely simple and practical device is afforded for the display and handling of articles or goods to be merchandised, and particularly for the display of specimen flowers and the like in promotion of the sale of seeds, bulbs, etc. The device is quickly and easily collapsed and extended, and when extended gives the observer a full and uninterrupted view of all of the contained articles in an attractive display of relatively large proportion. When collapsed the cabinet is brought into compact form of relatively small dimensions and the articles contained therein are entirely concealed. Thus, the cabinet is readily handled and transported in safety thereto and to its contents, the attendant being able quickly to present the attractive display afforded by the structure. In the collapsed relation of the cabinet sections, the absence of any partition walls between the specimens in the two cabinet sections provides for the full utilization of all of the available space by the stems, leaves and flowers in the display. 55 The cabinet may be constructed at a nominal cost from materials readily available and may be constructed in a neat and attractive manner.

Changes in the specific form of my invention, as herein disclosed, may be made within the scope of what is claimed without departing from the spirit of my invention.

Having described my invention, what I claim as new and desire to protect by Letters 65 Patent is:

1. A cabinet comprising two sections, each thereof being open at one side and at one end, said sections being hinged at their open ends one to the other and adapted to be relatively positioned in extended relation with their open ends together and in folded relation with their open sides together, each section having a rack therein, one rack constituting a continuation of the other rack in the extended relation of said sections. 70

2. A cabinet comprising two sections, each thereof being open at one side and at one end, said sections being hinged at their open ends one to the other and adapted to be relatively positioned in extended relation with their open ends together and in folded relation with their open sides together, and a closure, common to the two open ends of said sections, adapted to close said ends in the folded relation of the sections. 75

3. A cabinet comprising two sections, each thereof being open at one side and at one end, said sections being hinged at their open ends one to the other and adapted to be relatively positioned in extended relation with their open ends together and in folded relation with their open sides together, and a closure, common to the two open ends of said sections, adapted to close said ends in the folded relation of the sections, said closure being hinged to one of the sections and adapted to be swung out of closing position to avoid interference with the bringing of said sections into extended relation. 80

4. A cabinet comprising two sections, each thereof being open at one side and at one end, said sections being hinged at their open ends one to the other and adapted to be relatively positioned in extended relation with their open ends together and in folded relation with their open sides together, and a closure, common to the two open ends of said sections, adapted to close said ends in the folded relation of the sections, said closure being hinged to one of the sections and adapted to be swung out of closing position to avoid interference with the bringing of said sections into extended relation, the tops of said sections being hinged to the backs thereof and adapted to be swung back and supported by said closure. 100

5. A cabinet comprising two elongated sections, each thereof being open at one side and at one end, said sections being adapted to be relatively positioned in extended relation with their open ends together and in folded relation with their open sides together, each section having a plurality of racks extending lengthwise thereof, the racks of one section constituting continuations respectively of the racks of the other section in the extended relation of said sections. 105

6. A cabinet comprising two elongated sections, each thereof being open at one side and at one end, said sections being adapted to be relatively positioned in extended relation 110

with their open ends together and in folded relation with their open sides together, each section having a plurality of racks extending lengthwise thereof, the racks of one section constituting continuations respectively of the racks of the other section in the extended relation of said sections, and closure means removably applicable to the open ends of the sections in the folded relation thereof.

7. A unitary cabinet comprising two elongated sections, each thereof being open at one side and at one end, said sections being adapted to be relatively positioned in extended relation with their open ends together and in folded relation with their open sides together, and means movable into and out of operative position for closing the open ends of said sections in the folded relation thereof.

8. A cabinet comprising two sections, each thereof being open at one side and at one end, said sections being hinged at their open ends one to the other and adapted to be relatively positioned in extended relation with their open ends together and in folded relation with their open sides together, and a device constituting a combined closure and brace adapted to close the two open ends of said sections in the folded relation thereof, said device being hinged to one of the sections and adapted to be swung out of closing position, to avoid interference with the bringing of said sections into extended relation, into bracing position to steady the cabinet in its extended form.

9. A cabinet comprising two sections, each thereof being open at one side and at one end, said sections being adapted to be relatively positioned in extended relation with their open ends together and in folded relation with their open sides together, and means adapted to form a closure for said open ends in the latter relation of said sections and also adapted to form a brace for the cabinet in its extended form.

10. In testimony whereof I have affixed my signature to this specification.

RALPH BAERMAN.
